Specification of Letters Patent.

Patented Jan. 6, 1920.

Application filed June 19, 1919. Serial No. 305,245.

To all whom it may concern:

Be it known that I, EDWARD O. STERNS, a citizen of the United States, residing at Columbus, in the county of Franklin and 5 State of Ohio, have invented certain new and useful Improvements in Signs, of which the following is a specification.

This invention relates broadly to signs and illuminated advertising novelties, the 10 object of the invention being to provide a sign partaking of the general appearance of a pneumatic tire, and wherein novel correlation of parts is provided to permit the sign to be illuminated and to enable the 15 same to be constructed essentially of opposed securely united glass members.

Another object of the invention resides in a sign of the above character which is composed substantially of a pair of opposed 20 and separate glass members, the inner peripheral edges of said members being formed to fit in the recesses of a rim simulating structure, and the outer peripheral edges of said members being securely united in spaced 25 relation by a plurality of concentric rings, threaded elements being situated to unite said rings so that the latter may be retained in such operative positions as to effect a rigid and secure assembly of the several parts constituting the sign.

A further object of the invention resides in providing the inner of the member securing rings with illuminating devices, preferably in the form of incandescent lamps, 30 whereby when the latter are illuminated, the sign will present a pleasing and attractive appearance so that the same will be particularly efficient in carrying out its intended purpose.

With these and other objects in view, as will appear as the description proceeds, the invention accordingly consists in the novel features of construction, combination of elements and arrangement of parts hereinafter 45 to be fully described and to have the scope thereof pointed out in the appended claims.

In the accompanying drawing, forming a part of this specification, and in which similar characters of reference denote like and 50 corresponding parts:

Figure 1 is a fragmentary vertical sectional view taken through a sign constructed in accordance with the principles of the invention.

Fig. 2 is a transverse sectional view taken 55 along the line 2—2 of Fig. 1.

Referring more particularly to the structural details of the invention, the latter in the form exemplified in the accompanying drawing consists of a sign 1, which in this 60 instance is in the form of an automobile tire, whereby the sign when illuminated will pleasingly direct attention to the character of business with which it is employed. To provide a structure of this type wherein 65 the appearance of a tire is imitated, the present invention contemplates the provision of a pair of opposed, circular members 2 which are preferably formed from glass so as to be transparent or translucent. The inner 70 peripheral edges of each of the members 2 are provided with circular enlargements 3, which are adapted to be received within the curved outer edges 4 of a rim member 5. The latter is also provided upon its outer 75 face with projections 6, with which the contiguous edges of the rim members 5 engage, so that inward sliding movement on part of said rim members will be arrested by the projections so that the said members 2 will 80 be firmly received within the enlargements 3.

The outer edges of the members 2 are substantially spaced, as is indicated by the numeral 7, and to retain the members 2 in their respective positions, the same are provided with annular recesses 8, in which are positioned an outer ring 9. The members 2 further have their outer edges provided with curved offsets 10, which are engaged by similarly shaped edges 11 formed upon an inner metallic ring 12. The ring 12 is adapted to carry a plurality of insulated 90 lamp sockets 13, in which are positioned lamps 14, the latter being suitably wired to effect any desired character of intermittent 95 or continuous illumination. A conduit 15 leads through the rings 9 and 12 and is secured to the latter as at 16. This conduit may be employed for the purpose of carrying the circuit wires of the lamps 14 and 100 also may be employed in the capacity of effecting the suspension of the sign.

To retain the rings 9 and 12 in their properly assembled position, that is, in order that the ring 9 will lie within the recesses 8 105 and the ring 12 in engagement with the curved edges 11, use is made of a plurality of threaded elements 17, preferably in the form

of stove bolts. The latter in this instance pass through radially alined openings formed in said rings, and the ring 12 is provided with threaded openings 18, whereby when the bolts are securely threaded within said openings, the rings 9 and 12 will be drawn together and in this manner retained in rigid association with their respective points of contact with the glass members 2.

From the foregoing description taken in connection with the accompanying drawing, it will be apparent that there is provided a sign of considerable utility, and one wherein the several elements thereof will be capable of securely maintaining their assembled relation. Upon the illumination of the lamps 14, the sign will radiate light, and in this manner will be capable of attracting requisite attention. In assembling the parts, it is simply necessary to insert the members 2 so that their portions 3 will be seated in engagement with the edges 4 of the rim 5. The rings 9 and 12 are then loosely associated with their respective points of engagement with the spaced outer peripheral edges of the members 2, so that upon the rotation of bolts or screws 17, said rings will be drawn together and the members 2 thus rigidly clamped in assembled array. This method of assembling parts may of course be departed from, but for the structure set forth, this method may be efficaciously employed.

I claim:

1. A sign of the character described, comprising a pair of spaced glass members of tire resembling contour, the outer peripheral edges of said members being spaced, an outer ring disposed to encircle said members and to bridge the gap therebetween, an inner ring concentric to said outer ring and cooperative with the inner portions of said

sign, and clamping means for uniting said rings in assembled relation with said members.

2. In a sign of the character described, the combination with a pair of glass members shaped to define the configuration of a tire, of means for retaining the members in assembled relation, comprising a rim element disposed to engage the inner peripheral edges of said members, a plurality of concentric rings disposed to coöperate with the outer circumferential edges of said members, and securing devices carried by said rings and capable of clamping the latter in bound engagement with said members.

3. A sign of the character described, the combination with a pair of glass members shaped to define the general contour of a pneumatic tire, of means for rigidly assembling said members and to maintain the latter in spaced relation, comprising a rim device disposed to engage with the inner peripheral edges of said members, and a plurality of concentric ring elements coöperative with the spaced outer peripheral edges of said members to maintain the latter in spaced relation.

4. In a sign of the character described, the combination with a pair of opposed and spaced glass members, shaped to resemble a vehicle tire, a rim structure disposed to engage with the inner peripheral edges of said members to retain the latter against movement, and a clamping structure coöperative with the outer edges of said members to effect the assembling of the outer portions of said sign, said latter structure carrying a plurality of illuminating elements.

In testimony whereof I affix my signature.

EDWARD O. STERNS.
